DAN. GUPTAIL, OF ELGIN, ILLINOIS.

Letters Patent No. 89,216, dated April 20, 1869.

IMPROVED DISH-WASHING MACHINE.

The Schedule referred to in these Letters Patent and making part of the same.

To all whom it may concern:

Be it known that I, DAN. GUPTAIL, of Elgin, in the county of Kane, and State of Illinois, have invented a new and useful Improvement in Machines for Washing Dishes; and I do hereby declare that the following is a full, clear, and exact description of the same, reference being had to the annexed drawing, making part of this specification, in which—

Figure 1 is an elevation of my improved machine, with a portion of the casing broken away, to show the wire basket for holding the dishes, and a portion of the wheel which forces the water among such dishes.

Figure 2 is a plan or top view, with the cover removed, so as to expose to view the basket for the dishes, the water-agitator, and the guide, for giving direction to the water;

Figure 3 is an elevation of the frame for holding knives and forks while being washed; and

Figure 4 is a plan view of the same.

Corresponding letters refer to corresponding parts in all the figures.

This invention relates to that class of machines which are denominated dish-washers; and

It consists in the construction, combination, and arrangement of the parts of which it is composed, as will be more fully described hereinafter.

A, in the drawings, represents a case, which may be of the form shown in the drawings, figs. 1 and 2, and of any suitable dimensions, and may be made of tin, or other suitable material, it being provided with a cover, a portion of which is firmly secured thereto.

B represents the removable portion of the cover, it being that portion which is above the basket, into which the dishes are to be placed while being washed. The remaining portion is secured firmly to the sides of the case, and serves as the foundation of the stand, to which the upper end of the shaft of the agitator, and the gearing which drives the same, are secured.

C represents the agitator, which is to be placed within the smaller portion of the case, it being composed of shaft E, and having a cylinder secured thereto, to which buckets, or wings are attached, which in form are similar to the buckets of a water-wheel.

These buckets, in length, are about equal to the height of the case, and are designed to force the water among the dishes, which are placed in the wire basket for that purpose.

D represents a basket, which is to be made of open wire work, and is to be placed within the larger portion of the case, as clearly shown in figs. 1 and 2 of the drawings.

E represents the shaft of the agitator, stepped in a plate, which is secured to the bottom of the case, its upper end being secured by a plate of metal, which is bolted to the fixed portion of the cover.

F represents a bevelled pinion, which is secured to the upper end of shaft E, and which is driven by the wheel G.

G represents the driving-wheel, which is secured upon a shaft, which passes through bearings formed in

a frame-work, which is raised upon the plate secured to the top of the case.

The teeth of this wheel mesh into the spaces between the teeth on the pinion, and hence, as it is rotated, the agitator is made to revolve with rapid motion.

H represents a crank, which is secured to the outer end of the shaft, to which the larger gear-wheel is secured, it being for the purpose of giving motion to such gear-wheel.

I represents a disk of metal, which is provided with legs to rest upon the bottom of the case, the disk being so constructed as to form a receptacle for knives and forks, for which purpose it is provided with a series of slots, so that such articles may be inserted therein to be washed, as clearly shown in fig. 3 of the drawings.

It will be seen that when this disk is in use, it forms a cover to the open portion of the case.

K represents an adjustable spring-guide, which is to be attached to the case of the machine, and is so arranged that it may be used to contract the opening through which the water passes from the agitator to the other portion of the machine.

This guide, or regulator, is provided with a handle, which passes through the case, by which means the guide may be forced inward, so as to contract the passage, as above described, and thus give greater force to the water as it passes from the agitator, by which means a more thorough cleansing of the articles will be accomplished.

When articles are being cleansed which do not require the full force of the water, the guide K is to be drawn back, so as to enlarge the aperture through which the water passes, in which case less power applied to the crank will suffice to properly cleanse the articles.

I am aware that a patent was granted to Joel Houghton on the 14th of May, 1850, and another to Gilbert Richards and Levi Lancaster, October 13, 1863, designed for washing dishes, and having cases, or receptacles for holding the dishes, and wheels for forcing the water in contact with such dishes. I do not, therefore, claim, broadly, such devices; but, having thus described my invention,

What I claim, and desire to secure by Letters Patent, is—

1. The combination of the case A and the disk, or knife-holder I, substantially as shown and described.
2. The arrangement of the guide K, with reference to the case A and agitator C, substantially as shown and described.
3. The construction of the disk I, with its slots for holding the knives and forks, substantially as shown and described.

In testimony whereof, I have signed my name to this specification, in the presence of two subscribing witnesses.

Witnesses:

HOGEN WEBSTER,
EDMUND WHEDON.
